DESIGN FOR A VANITY CASE

Abraham Klein and Leo Esterow, New York, N. Y.,
assignors to Columbia Stamping Products Co.,
Inc., New York, N. Y., a corporation of New York

Application February 23, 1935, Serial No. 55,582

Term of patent 7 years

To all whom it may concern:

Be it known that we, Abraham Klein and Leo Esterow, citizens of the United States and residents of New York city, in the county of Queens and State of New York, have invented a new, original, and ornamental Design for Vanity Cases, of which the following is a specification, reference being had to the accompanying drawing, forming part thereof, in which:—

Figure 1 is a plan view of a vanity case, showing our new design, and Figure 2 is a side elevation of the same.

We claim:

The ornamental design for a vanity case, as shown.

ABRAHAM KLEIN.
LEO ESTEROW.
